Des. 232,610
Patented Sept. 3, 1974

232,610

CABINET FOR DRAWERS OR THE LIKE

Kenneth H. Petersen, 821 Index Court NE.,
Renton, Wash. 98055

Filed Nov. 24, 1971, Ser. No. 202,059

Term of patent 14 years

Int. Cl. D6—03

U.S. Cl. D6—186

FIG. 1.

FIG. 2.

FIG. 3.

FIG. 4.

FIG. 5.

FIG. 6.

FIG. 7.

FIG. 8.

FIG. 9.

FIG. 10.

FIG. 11

FIG. 12

FIG. 13

FIG. 1 is a top perspective view of a cabinet for drawers or the like showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a top perspective view of a modified form of the cabinet of FIG. 1 showing double units;

FIG. 7 is a top plan view of the cabinet of FIG. 6;

FIG. 8 is a bottom plan view of the cabinet of FIG. 6;

FIG. 9 is a right side elevational view of the cabinet of FIG. 6;

FIG. 10 is a front elevational view of the cabinet of FIG. 6;

FIG. 11 is a front elevational view of a modified form of the cabinet of FIG. 1 showing triple units;

FIG. 12 is a front elevational view of a modified form of the cabinet of FIG. 1 showing quadruple units;

FIG. 13 is a front elevational view of a modified form of the cabinet of FIG. 1 showing five units together.

The rear elevational view of the cabinet in each instance is the same as the front elevational view and the left elevational view in each instance is the same as the right elevational view.

I claim:

The ornamental design for a cabinet for drawers or the like, substantially as shown and described.
